UNITED STATES PATENT OFFICE.

ERNEST A. THOMFORDE, OF ENGLEWOOD, NEW JERSEY.

GRIPPING DEVICE.

SPECIFICATION forming part of Letters Patent No. 605,454, dated June 7, 1898.

Application filed April 29, 1897. Serial No. 634,487. (No model.)

To all whom it may concern:

Be it known that I, ERNEST A. THOMFORDE, a citizen of the United States, and a resident of Englewood, in the county of Bergen and 5 State of New Jersey, have invented certain new and useful Improvements in Gripping Devices, of which the following is a specification.

My invention relates to devices in which 10 an object is grasped and securely held by the coöperation of one or more movable jaws, and more especially to that class known as "bench-stops" or "vises," by which material may be secured during manipulation by the work- 15 man.

The objects of my invention are to, first, provide an effective and convenient form of bench-stop; second, provide an easily-adjustable device; third, provide means for holding 20 thin and small objects without injury, and, fourth, provide a device conveniently attachable to an ordinary carpenter's bench.

Heretofore bench-stops have consisted of 25 obstructions immovably attached to the bench and adapted to prevent the material being operated upon from moving in one direction, or where means have been employed to prevent backward motion they have been non-adjustable for different-sized objects or have 30 been of such nature as to injure the work or insufficiently hold small or thin material, and where the devices have been movable or adjustable they have not been of such a nature as to allow support of a long piece, and thus 35 prevent distortion by its own weight or the effort of manipulation. I obviate these objections by making my bench-stop adjustable in height to give a firm grip to material of varying thickness and adjustable in width in 40 order to engage material of varying width. By providing a gripping-lever I am able to prevent backward motion during manipulation, and by adapting the device to be set into the surface of a bench I am able to secure the coöperation of the same to prevent 45 sagging or distortion, as in the use of the ordinary side vise, and by making the stops adjustable in height and the bed countersunk I am also able to have the upper sur- 50 face of the bench free from obstruction when the device is not in use.

I accomplish the object of my invention by

the means shown in the accompanying drawings, in which similar letters of reference refer to similar parts throughout the several 55 views.

Figure 1 is a plan view of my device, showing a piece of wood held thereby. Fig. 2 is a plan of a removable cover for the device, Fig. 3 is a perspective view from the side. 60 Fig. 4 is a sectional view from the end, showing the adjusting and locking device.

Referring to Fig. 1, A represents a table or bench, in which the device is set so as to be flush with the top surface and to which it 65 is secured by screws.

B is the body of the device and preferably consists of a casting formed with a flange l, which sets flush with the top of the table, as stated. It is sunk or hollowed on top to allow the portions C and D to lie flush within 70 it when pushed down or not in use.

C is a bench-stop with the usual teeth P, which is capable of being raised or lowered and is maintained in position by the spring 75 L. (See Fig. 3). The screw K', as shown in the drawings, is intended to lock the part C to the shank M. It may, moreover, be entirely omitted from the device and the part C and the shank M be made integral. It is 80 made curved and sharp at R, so as to grip the material securely.

D is a clamp mounted on spring-fitted post L and M, Fig. 2, by which it can be raised or lowered in the block or carriage F, which is 85 free to slide along the ways S, and is pivoted to the top of said post M at K, thus being free to move in a horizontal plane and grip the material in conjunction with the stop C, as hereinafter more explicitly pointed out. 90

The sliding adjustment of the block F is regulated by the manipulation of the lever-catch G, pivoted to F at J, by engaging the teeth H of the slotted bed. When not in use, the depression in the bed B may be filled by 95 a cover T, cut to fit inside of the flange l and abut against the clamp D, thus being flush with the flange l and the table A and so preventing chips or refuse from clogging the device.

The operation of the device is as follows: When it is desired to plane or work a piece of material of sufficient dimension, the stop C may be raised and the work abutted against

the notches P, as usual with the ordinary bench-stop of this class. When a narrow strip is to be manipulated which would be imperfectly held or injured by the notches P, the lever G is moved so as to engage with a notch suitable to the width of the piece and the piece inserted between the clamp D and the stop or clamp C. The piece pressing against the long arm R' of the lever-clamp D turns it on its pivot K, so that the end is forced firmly against the piece, gripping it tightly at the points R, R', R², and R³. It is evident that work of varying width may be similarly held by adjusting with the catch G, as above described, the points R R' being normally nearer together than the points R² R³. The horizontal pivotal movement of the clamps C and D supplies the finer adjustment and gripping effect necessary to firmly hold the material. When not in use, the cover T, Fig. 2, is placed in position, when the whole device presents a closed surface flush with the bench-top.

I am aware that fixed bench-stops of varying height with teeth or notches have long been known in the art and also that pivoted lever-clamps adapted to engage material between their contiguous extremities are known. I do not, therefore, claim them broadly; but 30 What I do claim, and desire to protect by Letters Patent, is—

1. In an organized device for holding objects on work-benches, the combination of a vertically-adjustable serrated bench-stop, an independent vertically-adjustable gripping device, pivoted so as to automatically coöperate therewith horizontally, and means for locking the same in position, substantially as described.

40 2. In an organized device for holding objects, the combination of a vertically-adjustable serrated bench-stop, an independent vertically-adjustable gripping device adapted to move horizontally and automatically coöperate with the bench-stop, and a stop adapted to engage with the body of the device, controlling the lateral movement of the gripping device.

3. In an organized device for holding objects on a work-bench, the combination of a tray countersunk to receive the component parts, a vertically-adjustable rigid serrated

bench-stop, a vertically-adjustable gripping device, pivoted so as to move horizontally and coöperate with the serrated stop, and a locking device adapted to engage with serrations in the body of the tray to regulate the lateral movement of the gripping device.

4. In an organized device for holding objects on work-benches, the combination of a tray countersunk to receive the component parts flush with the surface of the bench, a bench-stop fitted therein, and adapted to be adjusted perpendicularly thereto, an independent perpendicularly-adjustable clamp, adapted to coöperate with the bench-stop to secure an object between them by means of the insertion thereof, and means for adjusting the clamp laterally in said tray.

5. In combination, for the purposes described, a countersunk tray adapted to receive the component parts flush with the upper surface, a rigid but vertically-adjustable serrated bench-stop, having its interior face concaved in the direction of its length, a vertically-adjustable clamp having its interior face similarly concaved and adapted to coöperate with the bench-stop to grip an object between them by its insertion, a sliding block bearing the clamp, and a lever on said block adapted to engage with the tray, substantially as described.

6. In an organized device for holding objects on work-benches, the combination of a vertically-adjustable serrated bench-stop; an independent vertically-adjustable gripping device pivoted so as to rotate horizontally and automatically coöperating therewith, and means for locking the same in position, substantially as described.

7. The combination of a vertically-adjustable bench-stop, an independent vertically-adjustable clamp, adapted to coöperate with the bench-stop to secure an object between them by means of the insertion thereof, and means for adjusting the clamp laterally.

Signed at Englewood, in the county of Bergen and State of New Jersey, this 7th day of April, A. D. 1897.

ERNEST A. THOMFORDE.
